AEROSOL BOMB

Robert S. Knapp, St. Louis, Mo., assignor, by
mesne assignments, to Knapp-Monarch Com-
pany, St. Louis, Mo., a corporation of Delaware

Application September 18, 1946, Serial No. 697,805

3 Claims. (Cl. 299—95)

1

This invention relates to a spraying device in which a container of liquid is charged with gas from a sealed bulb or the like and thereafter the gas within the container acts on the liquid to displace it through a discharge opening whenever a valve for the opening is moved to open position. The device is particularly adapted to serve as an aerosol bomb.

One object of the invention is to provide a liquid spraying device having a valve of novel construction that eliminates the usual valve seat and valve plug, petcock or other type of valve usually provided for controlling the flow of liquid under pressure.

Another object is to provide an aerosol bomb which is readily refillable and rechargeable with gas pressure for dispensing the liquid contents.

Still another object is to provide an assembly of container, discharge valve, bulb holder and piercing unit in which the bulb holder serves conveniently as a handle for the aerosol bomb.

A further object is to provide a valve structure in which a capillary tube extends from the discharge nozzle into a fluid delivery passageway and has a packing surrounding it, the inner end of the tube being sealed and the tube being provided with an opening that is normally exterior of the packing but may be adjusted to a position interior thereof for permitting fluid flow, the tube being returnable by spring pressure and the valve being thereby openable by thumb pressure in opposition to the spring pressure.

With these and other objects in view, my invention consists in the construction, arrangement and combination of the various parts of my device whereby the objects contemplated are attained, as hereinafter more fully set forth, pointed out in my claims and illustrated in the accompanying drawings, wherein:

Figure 1 is a vertical sectional view through an aerosol bomb embodying my invention and showing the device approximately full size.

Figure 2 is an enlarged sectional view of the valve structure of the bomb showing the valve in open position as distinguished from the closed position of Figure 1; and

Figure 3 is a further enlarged sectional view on the line 3—3 of Figure 2 showing details of construction of the valve.

On the accompanying drawing, I have used the reference character 10 to indicate a container adaptable to contain liquid 12 under high pressure. The container 10 has a bottom 14 and in its upper end a threaded boss 16 is soldered or brazed.

A body member B is screwed into the boss 16 with a suitable gasket 18 interposed between the two to prevent leakage. The body B has a nozzle 20 screwed into it for projecting laterally there-

2

from. The body is provided with a threaded nipple 22 projecting in the opposite direction.

A bulb holder 24 is adapted to be screwed onto the nipple 22 and contains a bulb 26 of CO₂ gas, air or the like under high pressure. The bulb 26 has a puncturable cap 28 adapted to be propelled toward a piercing pin 30 in a well-known manner by means of screwing the bulb holder 24 into position.

The piercing pin 30 is hollow so as to receive gas from the bulb and such gas passes through the threads of a plug 32 to a passageway 34 leading into the boss 16 and the container 10, where it acts on the liquid 12 to displace the same as will hereinafter appear. The threads of the plug 32 permit but very slow flow of the gas. This arrangement prevents the possibility of the gas from the bulb being applied suddenly to the container 10.

Surrounding the neck of the bulb and spaced from the piercing pin 30 is a rubber sealing sleeve 36 which seals the neck of the bulb relative to the body B as soon as the bulb is associated with the body member and before its cap is pierced.

A syphon tube 38 is screwed into the bottom of the body member B and terminates in a bell-shaped reception fitting 40 at its lower end. The fitting 40 is located in a sump 42 of the container bottom 14.

The upper end of the syphon tube 38 communicates with a bore 44 in the body member B in which is slidably mounted the lower end of a capillary tube 46. The bore 44 is only slightly larger in diameter than the diameter of the capillary tube.

Above the bore 44 is a packing washer 48 held in position by a packing gland 50. The tube 46 is slidable through the elements 48 and 50 and has an opening 52 normally located above the packing washer as shown in Figure 1.

The tube 46 after extending upwardly bends laterally and enters the nozzle 20, being confined in a bore 54 thereof. The bend of the tube passes through the bottom of a cup member 56 and through the side of a valve depresser 58. The cup and depresser are normally held in the raised position of Figure 1 by a spring or restoring means 60. They are limited in the upward direction by a thumb button 62 having a projection 64 pivoted in a socket 66 of the body member B and a stop projection 68 engaging a cup-shaped retainer 70. The retainer 70 is held in position by the nozzle 20.

The capillary tube 46 is closed at its lower end as indicated at 72 and together with its opening 52 the packing washer 48 and the bore 44 constitutes a valve that prevents fluid flow when the parts are in the position of Figure 1. When the thumb button 62 is depressed it will, through the valve depresser 58, bend the tube 46 inwardly of

its anchored discharge end in the bore 54 of the nozzle 20 and move the tube so that its opening 52 is below the packing washer 48 instead of above it. This is the position shown in Figure 2. The valve is now open and the liquid 12 under pressure can flow upwardly in the syphon tube 38 and the bore 44 and then through the opening 52 into the capillary tube 46, finally discharging in the form of a very fine atomized spray indicated at 74 in Figure 2. After the desired quantity of liquid has been dispensed the thumb button 62 can be released whereupon the spring 60 will propel the parts back to the initial position of Figure 1. This arrangement provides a very simple valve structure which will give long life and trouble free operation.

It will be noted that the boss 16 extends downwardly into the container 10 which precludes filling the container above the level of liquid shown in Figure 1. This leaves the necessary space for the introduction of gas under pressure from the bulb 26.

The external diameter of the capillary tube 46 is but slightly smaller than the internal diameter of the bore 44 as shown in Figure 3. In a valve of the size shown in Figure 1 for instance the outer diameter of the tube may be approximately .028" and the internal diameter of the bore about .006" to .008" larger. This will give a space all around the capillary tube that is .003" to .004" wide. This results in a maximum area in the space between the tube and the bore of approximately .0008" which is only two twenty-fifths of one percent of one square inch. This is the area over which the pressure in the syphon tube 38 is exerted against the packing washer 48. Being very small, the force (pressure $\times$ area) will produce only approximately .12 lb. per sq. in. pressure on the packing when the container is charged with gas at 150 pounds per square inch. The pressure on the packing is accordingly substantially negligible as distinguished from the pressures involved in most types of valves.

From the foregoing specification it will be obvious that I have provided a simple type of refillable insecticide dispenser or aerosol bomb which can be conveniently charged with the required pressure for discharging liquid in aerosol form by association of a compressed gas bulb with the bomb. It will be noted that the bulb holder is in such position with relation to the container and to the thumb button 62 that it serves conveniently as a handle for supporting the device and the thumb button can be readily depressed by the thumb of the hand holding the bomb.

The valve acts as a positive seal when closed and the bomb can therefore be used intermittently with long periods of non-use yet is always ready to use when needed. When the bomb is emptied of liquid, this fact is denoted by the discharge of gas instead of liquid when the valve is open. Refilling is readily accomplished by unscrewing the body member B from the container 10 and after filling, the bomb is readily recharged with pressure from a bulb. These operations require a minimum of time.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In an aerosol bomb of the character disclosed, a container for liquid, a body member removably positioned on said container and having a passage leading to the container, and a valve structure mounted in said body member for controlling the discharge of liquid from said container, said valve structure including a discharge nozzle mounted rigidly on said body member, a push button operable by the thumb of the hand holding said body member and a tube having a portion reciprocated thereby and another portion extending laterally to said discharge nozzle and bending during the valve opening and closing operations, said first portion having a closed end in said passage, packing around said portion, said portion having a lateral opening adapted to be selectively located either inwardly or outwardly of said packing.

2. In a structure of the character disclosed, a body member having one portion adapted for communication with the interior of a container of liquid under pressure, and a valve for controlling the discharge of liquid from said body portion through said body member comprising a tube slidably mounted in said body member, packing means around said tube, said tube being closed on its inner end and having an opening positionable outside or inside said packing means to prevent or permit fluid flow respectively, said tube having a laterally extending discharge portion terminating in a fixedly anchored discharge end and bendable between said end and the slideable portion of the tube to permit of such sliding in relation to said fixed discharge end.

3. In a structure of the character disclosed, a container for liquid, and a valve for controlling the discharge of liquid comprising an element having a passageway communicating with said container, a tube section slidably in said passageway and closed at its inner end, packing means around said tube section, said tube section having an opening positionable outside or inside said packing, said opening when in said inside position communicating with said passageway, said tube having a discharge section, one end of which is fixed in relation to said element and said discharge section being bendable between the fixed end and the other end thereof, a manually engageable element for sliding said first tube section, and restoring means to return said element upon manual release thereof.
